UNITED STATES PATENT OFFICE

2,376,652

CONTROL DEVICE

Merton O. Bassett, Schenectady, N.Y., assignor to
General Electric Company, a corporation of
New York

Application November 20, 1943, Serial No. 511,058

5 Claims. (Cl. 200—106)

My invention relates to control devices, more particularly to electromagnetically latched motor starting switches, and has for its object a simple, reliable and inexpensive electromagnetic motor starter which is shockproof.

When an electromagnet is subjected to shocks with its armature in its attracted position, the armature, if the shock is severe enough, is thrown from its attracted position against the holding force of the magnet. I have found that when the magnet is pivotally mounted, the force of the shock produces oscillation of the magnet on its pivot without throwing the armature from its attracted position. In fact, I have found that with such a mounting a relatively small amount of power supplied to the magnet is sufficient to hold the armature in its attracted position against a very severe shock whereas when the magnet is mounted solidly on a support, the coil cannot in some cases be energized strongly enough to hold the armature in its attracted position because the magnet structure becomes saturated before enough pull is developed to resist the force of the shock.

In carrying out my invention in one form I provide a holding electromagnet which, under normal conditions, is energized thereby to hold its armature in an attracted position, the armature in turn maintaining the switch in a closed position. In accordance with my invention, I mount the holding magnet and its armature on a pivot for movement in response to shocks and provide a latching portion on the armature which, with the armature in its attracted position, has its latching surface for holding the switch closed lying on the pivot axis of the magnet. With this arrangement, when the device is subjected to shocks, the magnet is free to move about its pivot but in doing so does not move the latching surface of the armature, since that surface lies on the pivot axis, and therefore maintains the switch in its latch closed position.

For a more complete understanding of my invention, reference should be had to the accompanying drawing in which Fig. 1 is a front elevation view of an electromagnetic motor starter embodying my invention; Fig. 2 is a side elevation view of the device shown in Fig. 1; Fig. 3 is a simplified exploded view of the device shown in Figs. 1 and 2 showing the holding mechanism in its latched position; while Fig. 4 is a view similar to Fig. 2 but showing the latching mechanism in its reset position.

Referring to the drawing, I have shown my invention in one form as applied to the operation

of a switch of the type described and claimed in U. S. Patent 2,291,466, issued on July 28, 1942, to Leon J. Goldberg. This switch is provided with an arc chute member 10, held in place by knobs 10a and 10b, which encloses stationary and movable contacts (not shown). The movable contacts are mounted on a rotatable member or shaft 11 made of a molded electrically insulating material and mounted for rotation on bearing posts 12 and 13 secured to a suitable panel support 14. The shaft 11 is turned to close and open the switch by means of an arm 15 secured to the shaft adjacent the bearing post 13, this arm and the shaft being turned clockwise from the position shown in Fig. 2 by pressing manually a button 16 toward the right hand, as seen in Fig. 2.

As shown most clearly in Fig. 3, the button 16 is on the end of a link 17 slidably mounted in a member 18 mounted on one arm 19 of a U-shaped support 20 having a second arm 21, this support being secured to the panel 14. At its lower end the link 17 is pivotally connected at 22 with an arm 23 having one end mounted on a stationary pivot 24 and its other end pivotally connected at 25 to a link 26. The upper end of the link 26 is pivotally secured to a rod 27 which in turn is connected to a latch and cam operating or control member made in two identical parts 28 and 29. These two parts 28 and 29, are secured rigidly together in slightly spaced parallel relation with each other by the rod or bolt 27 so that together they constitute a latch and cam member. They are pivotally mounted on a rod 30 mounted on the arms 19 and 21. Between these two members 28, 29 extends the lower end of the arm 15 which carries a pin or bolt 31 extending at its opposite ends through cam slots 32 and 33 in the members.

These cam slots are identical in shape and size. They extend in such directions with respect to the pivot shaft 30 that when the latch member 28, 29 is moved on the pivot shaft, the end of the arm 15 is moved with respect to the pivot shaft thereby to turn the shaft 11 and operate the switch. Thus the upper ends of the slots are quite near the pivot shaft 30 and the slots extend in parallel relation with each other away from the pivot shaft. With the switch in its tripped open position shown in Fig. 2, when the button 16 is depressed the cam member 28, 29 is turned clockwise on the pivot shaft 30 through the linkage 23, 26 and the operating pin 27. This movement causes the lefthand walls of the slots, as seen in Fig. 2, to engage and push the pin 31 away from

the pivot shaft 30 and turn the switch shaft 11 clockwise to its closed circuit position.

The other ends of the slots terminate in portions substantially tangential with respect to radii passing through the axis of the pivot shaft 30. Consequently when the button has been fully depressed, as shown in Fig. 3, the arm 16 has been turned to its maximum position in a clockwise direction and the ends of the pin 31 lie in these tangential portions of the slots, i. e., the lower portions of the slots, as seen in Fig. 3. When in these tangential slot portions, no clockwise force is applied by the shaft 31 to the inner walls of the slots, and the force is then in a direction passing through the center line of the shaft 30. Thus the force holding the arm 16 and the shaft 11 in the closed circuit position against the bias of the opening spring 35 attached to the link 26 does not tend to produce any rotation of the cam member 28, 29.

For the purpose of holding the cam member 28, 29 in its switch closed position, projections 36 and 37 are provided on it on the side of the pivot shaft 30 opposite the slots 32, 33. These projections extend under the lower end of a pivoted armature latch 39 of an electromagnet or electro-responsive means provided with a stationary magnet core 40 and an operating coil 41 whereby the member 28, 29 is held in this switch closed position.

For the purpose of making the electromagnet free from shocks which tend to throw the armature away from its attracted position against the pull of the magnet, the magnet is pivotally mounted on pins 42 and 43 on opposite sides which are secured to the arms 19 and 21, these pins 42, 43 being in alignment with each other as well as being parallel with the operating rod 17 and the pivot shaft 30. As shown, the pins 42 and 43 are attached to the lower left-hand sides of side plates 44 and 45 forming a support secured to the lower arm of the U-shaped magnet core, as seen in Fig. 3. Thus the magnet is unbalanced on the pins 42 and 43 in a clockwise direction, as seen in Fig. 3. These plates are provided with suitable notches 46 and 47 through which extend trunnions on opposite sides of the armature 39 whereby the armature is pivotally mounted on them.

A helical spring 48 is provided at the end of the lower arm of the core opposite the pins 42 and 43, the spring having one end secured by a screw 49 to the magnet core and its opposite end secured to the panel support 14. This spring 48 normally holds the magnet in a predetermined angular position about the pivot pins 42, 43, preferably substantially parallel with the panel, as seen in the drawing. Upon the occurrence of a shock, however, this spring yields to provide for oscillatory movement of the magnet on the pins 42, 43, which movement takes place because of the unbalance of the magnet about its supporting pins 42 and 43.

As seen in Fig. 3, the lower end of the armature 39 extends downward to a position in which the surface of this lower end in engagement with the latching projections 36, 37 passes through the center line of the pins 42, 43, i. e. the pivot axis of the magnet. Consequently, oscillatory movement of the magnet on the pins does not move the armature with respect to the latching projections but simply pivots the engaging points or surfaces of the armature on the projections. This occurs without any tendency to release the projections because of the fact that the armature does not

move relative to the projections but simply pivots on the projections. A helical tension spring 50 is provided having one end connected to the right-hand end of the armature, as seen in Figs. 2 and 3, and its other end connected to a stationary supporting member whereby the armature is biased to its unattracted position, as shown in Fig. 2.

For the purpose of returning the armature 39 to its attracted position when the switch is closed, 10 the member 28, 29 is provided with projections 51 and 52 which extend upward, as seen in Fig. 3, from the projections 36 and 37. Thus when the button 16 is depressed with the switch open, as 15 seen in Fig. 2, the members 28, 29 are turned until the projections 36, 37 have moved past the right-hand end of the armature, as seen in Fig. 2. Shortly after this, the projections 51, 52 engage the armature and, as a button is further depressed, 20 these projections push the armature to its attracted position, as shown in Fig. 4. It being assumed that the coil 41 is energized, the button 16 may now be released whereupon the member 28, 29 moves back somewhat in a counterclockwise direction until the projections 36, 37 are 25 brought to rest against the end of the armature.

It will be understood that the electromagnetic pickup force applied to the armature when the coil 41 is energized is not sufficient to start movement of the armature toward its attracted position against the force applied by the spring 50. This provides for the resetting of the cam member 28, 29, i. e., the movement of the projections 36 and 37 past the right-hand end of the armature, as seen in Fig. 2, prior to the movement of the armature to its attracted position, this movement of the armature being at least started by the projections 51 and 52.

The switch can be opened by opening the circuit 40 of the coil 41 by a suitable switching means (not shown) whereupon the armature is moved to its unattracted position by the spring 50 and the member 28, 29 thereby released. Also, it will be understood that, in the event of failure of voltage 45 for any reason, the coil 41 is deenergized to effect the opening of the switch.

What I claim as new and desire to secure by Letters Patent of the United States, is:

1. The combination with a control device provided with a control member biased to a predetermined position, of shockproof latching means for holding said control member in a second position comprising a support, means pivotally mounting said support for movement on an axis about which said support is unbalanced, resilient means for holding said support in a predetermined normal position about said axis thereby to provide for oscillation of said support about said axis in the event of a shock applied to said device, a latch member for said control member movably mounted on said support, and electroresponsive means on said support for holding said latch member in a predetermined position in which said latch member engages said control member 55 at a point lying substantially on said axis and for effecting movement of said latch member to release said control member.

2. The combination with a control device provided with a control member biased to a predetermined position, of shockproof latching means for holding said control member in a second position comprising an electromagnet provided with a pivotally mounted armature, means pivotally mounting said electromagnet for movement on an axis about which said electromagnet is unbal-

anced, spring means for holding said electromagnet in a predetermined normal position about said axis thereby to provide for oscillation of said electromagnet about said axis in the event of a shock applied to said device, latching means operated by said armature for engaging said control member when said armature is in its attracted position at a point lying substantially on said axis thereby to hold said control member in said second position, and means biasing said armature to an unattracted position to release said control member when said electromagnet is deenergized.

3. A control device comprising a switch, means for moving said switch to a closed circuit position, a magnet provided with an armature mounted for movement between attracted and unattracted positions, a latching member for holding said switch in its closed position engaging said armature when said armature is in one of said positions, and means pivotally mounting said magnet for oscillatory movement about a pivot axis passing through the point of engagement of said latching member with said armature.

4. A control device comprising a switch, means for moving said switch to a closed circuit position, a magnet provided with a pivotally mounted armature, latching means for holding said switch in its closed position engaging one end of said armature when said armature is in its attracted

position, and means pivotally mounting said magnet for oscillatory movement about a pivot axis passing through the point of engagement of said latching member with said end of said armature.

5. The combination with a movable member of shockproof latching means therefor comprising a support, pivot mounting means for said support providing an axis about which said support is unbalanced, resilient means for holding said support in a predetermined normal angular position about said axis thereby to provide for oscillation of said support about said axis in the event of a shock applied to said mounting means, a latch member for said movable member movably mounted on said support, and holding means on said support for maintaining said latch member in a predetermined latching position relative to said support and for effecting movement of said latch member to release said movable member, said latch member being provided with a latching surface for engagement with said movable member lying substantially on said pivot axis of said support when said latch member is in said predetermined latching position so that said oscillation of said support about said axis is ineffective to release said latch member from said movable member.

MERTON O. BASSETT.
